UNITED STATES PATENT OFFICE

ERNEST SPANOS, OF NEW YORK, N. Y.

AUTOMATIC SANITARY TOILET-SEAT PROTECTOR.

1,265,272.

Specification of Letters Patent.

Patented May 7, 1918.

Application filed May 20, 1916. Serial No. 98,793.

To all whom it may concern:

Be it known that I, ERNEST SPANOS, a subject of the King of Greece, residing in the city of New York, borough of Manhattan, county and State of New York, have invented certain new and useful Automatic Sanitary Toilet-Seat Protectors, of which the following is a specification.

This invention is an automatic sanitary 10 toilet seat protector and the object of the invention is the provision of means for automatically and intermittently advancing a web of tissue across a toilet seat so that a clean or fresh portion of the web will be 15 presented to each successive person using the seat.

A further object of the invention is the provision of mechanism which will shear off and deposit the portions of the web, as 20 successively used, into the bowl so that when the bowl is flushed, said used portions of the web are carried away.

It has heretofore been suggested to pass a protective web across the toilet seat for 25 sanitary and hygienic reasons well understood, but the structures which have been suggested for use have generally been actuated by movement of the seat cover or by other means which required manual operation 30 while the party was occupying the seat. The objection to these devices was that in the first instance the cover is not always operated, and in the second instance the manual operations necessary are generally overlooked. Accordingly, the devices of this 35 type were not positive in their operations and the successive users of the toilet were not automatically presented with unused portions of the web. Aside from the foregoing disadvantages, many others exist in 40 these types of device with the result that such constructions have never gone into use. The present invention overcomes the foregoing disadvantage in that it absolutely assures 45 intermittent movement of the web between successive uses of the toilet.

Speaking generally, the invention embodies a web, preferably of tissue paper, which is drawn over the seat by a feed roll, 50 movement of which is governed by pivotal movement of the seat itself. That is to say, the seat is normally maintained in a slightly raised position, and when the person sits upon the seat, the seat is depressed, whereupon 55 certain agencies are brought into play

which, when the person rises from the seat, automatically advance the web. The used portion of the web may be deposited within a suitable receptacle or may, in accordance with this invention, be deposited within 60 in the bowl and carried away during the flushing of the bowl.

Features of the invention other than those specified will be apparent from the following description, read in conjunction with the 65 accompanying drawings.

In the accompanying drawings, I have illustrated different practical forms of the invention, but the structures therein shown are to be understood as illustrative only 70 and not as defining the limits of the invention.

Figure 1 is a front elevation of a toilet bowl and seat showing one embodiment of the present invention mounted thereon, the 75 seat being shown in depressed position.

Fig. 2 is a plan view of the arrangement shown in Fig. 1.

Fig. 3 is a front elevation similar to that shown in Fig. 1, but with the seat shown in 80 its normally elevated position.

Figs. 4 and 5 are views corresponding to those of Figs. 1 and 2, but illustrating a modified form of the invention.

Fig. 6 is a transverse section taken in the 85 plane of the line 6—6 of Fig. 5.

Fig. 7 is a fragmental view, similar to Fig. 1, illustrating a slightly modified form of the invention.

Referring to the drawings, A designates 90 the usual bowl to which a seat B is pivoted at its back by means of a hinge and pin connection b. Secured to the under side of the seat, by any suitable means, and at the left-hand side thereof is a plate C which extends beyond the lateral edge of the seat and is formed into an elongated semi-cylindrical pocket c adapted to contain a roll of tissue paper D. A suitable cover c', of substantially semi-cylindrical form, is pivoted 95 along its edge to the edge of the pocket as at c' and serves to normally close the pocket and house the roll D. Formed at the front and back of plate C are two upstanding lugs e which carry a horizontal directional roller E, the top of which is substantially flush with the top of the seat B.

Mounted at the other side of the seat, and on the under side thereof, are two brackets f which extend laterally of the seat and 110

support the shaft f' near its opposite ends. A feed roll F is fixed on shaft f' and the parts are so associated in proportion that the top of the feed roll F is substantially 5 flush with the top of seat B. Tissue paper is adapted to be uncoiled from the roll D, extend through a slit intermediate the free edge of the cover c' and the pocket c, pass over the directional roller E, and thence extend 10 across the top of the seat and about the feed roll F, and means is provided for intermittently rotating the feed roll F to move said web across the seat with alternate feeding movements and periods of rest 15 or dwell.

Affixed to the forward end of shaft f' is a cam or ratchet g, provided with a shoulder g' , with which shoulder co-operates a pawl g^2 pivoted to a pinion g^3 loosely 20 mounted on shaft f' . Meshing with pinion g^3 is a rack G which is pivoted at h to a depending arm h' of the forward bracket f. Rigidly associated with respect to the rack G is an arm i, to the free end of which is 25 pivotally secured a link i', and the other end of said link is fixed against longitudinal movement on an extension i² of a plate i³ secured in any suitable manner to the bowl and free from connection with the 30 seat. This plate i³ may be provided with a clamp for detachably securing it to any stock bowl or may be secured directly thereto by screws as shown.

Because of the brackets f, which rigidly 35 support shaft f' with respect to the seat, and the plate i³, which precludes longitudinal movement of link i', it will be manifest that pivotal movement of the seat will necessarily impart pivotal movement to the 40 rack G, with the result that the pinion g^3 will be rotated. The parts are so formed that when the pinion is rotating in a counter-clockwise direction, the pawl g^2 will ride idly over the cam g, whereas, when the 45 pinion is rotated in a clockwise direction, the pawl will engage with the shoulder g' of the cam and drive the feed roll in a clockwise direction. It will be noted that when the seat is lowered, the movement of 50 the pinion will be in a counter-clockwise direction and no movement of the feed roll will result but, when the seat is raised, the movement of the pinion will be in a clockwise direction and the feed roll will be advanced. 55

The seat is normally maintained in the slightly elevated position shown in Fig. 3 by means of a helical spring secured at one end to the depending portion h' of the 60 forward bracket f and at its other end to the rack carrying member G. The tension of the spring normally impels the rack in the position shown in Fig. 3 and, by so doing, imposes the weight of the seat upon 65 the link i', thereby lifting the seat, through

the medium of the arm i, into the slightly elevated position shown. When weight is imposed upon the seat, as by a person sitting down, the tension of the spring J is overcome and the seat is depressed, carrying with it the forward bracket f, its depending arm h' and the pivotal point h of the rack. The free end of the arm i is precluded from such downward movement so that the rack is rotated into the position 70 shown in Fig. 1. During this operation the rack rotates the pinion g^3 in a counter-clockwise direction and places the spring J under tension. As soon as the person rises from the seat B, the parts assume their initial position, the rack G rotating the pinion in a clockwise direction and turning the feed roll F with the result that the paper web D is advanced. 80

The feed roll F and the ratio between the 85 teeth of the pinion and those of the rack are such that when the rack D travels its length past the pinion, the feed roll F will be rotated a sufficient number of times to advance paper web D to such extent as to 90 present a clean, unused portion of the web over the seat. To preclude the feed roll F from over-traveling because of its inertia of rotation, the roll is provided with a stop or shoulder f^2 which comes into engagement 95 with a finger g^4 , formed on the rack carrying member G, when the rack is in its forward position, the position which it assumes at the terminus of its travel under the impulse of spring J. Accordingly when 100 the rack has completed its travel in this direction, the finger g^4 is positioned in the path of the stop f^2 so that when the roll has been advanced the pre-described distance further movement of said roll is pre-105 cluded. Thus the stop f^2 and finger g^4 likewise serves to place the shoulder g' of the cam g in proper position to be subsequently operated upon by the pawl g^2 . Moreover, to preclude the rack G from traveling too 110 far, a stop k is formed on portion h' of the forward bracket which engages with the cam member g as shown in Fig. 3 when the same has reached the terminus of its forward travel. The parts are, therefore, at 115 all times maintained in adjustment so that just the proper amounts of paper web are successively fed across the seat.

To facilitate the advancing of the paper web and to assure the proper driving operation of the roll F, a pressure roll F' is 120 provided which is resiliently impelled against the periphery of the feed roll F, and the paper web is passed between these rolls so that sufficient friction is assured 125 as will preclude slipping.

Of course, the used portions of the paper web, after passing out of the feed roll, are no longer of any use whatsoever and it is desirable to dispose of them in some simple 130

and convenient manner. In the accompanying drawings I have illustrated two methods for the disposition of this used material.

- In Figs. 1, 2 and 3 of the drawings I have 5 shown means whereby the used portion of the web is coiled or rolled up after leaving the feed roll F, while in Figs. 4, 5 and 6 mechanism is shown for cutting off and depositing the used portions within the bowl A.
- 10 In carrying out the first mentioned form of invention, a cylindrical receptacle L is positioned directly below the feed roll and through said receptacle extends a shaft l on the rear end of which is mounted a pulley l'.
- 15 On the corresponding end of the shaft l' is mounted a coöperating pulley l² and pulley l' is drawn from pulley l² through a belt l³. In initially adjusting the web, the end of the web is suitably secured to the shaft l inter- 20
- 20 orally of the discharge casing L so that during the operations of the feed roll F in advancing the web, the used portions of the web, after leaving the feed roll, are wound upon shaft l within the discharge casing. The 25 belt drive between shafts l' and l is preferred since it allows of slipping as the roll of used web becomes larger within the discharge casing L.

In the modified form of the invention 30 shown in Figs. 4, 5 and 6, the web D, instead of passing around the feed roll F, passes around a directional roll m which maintains the web in contact with the feed roll. After leaving rolls m and F, the web 35 engages with the upper surface of a plate n, which guides the web between the lower face of the seat and the upper surface of the bowl into the interior of the bowl. Mounted between brackets o, which correspond to the 40 brackets f of the preferred form, is a fixed knife blade o', and pivoted to the rear bracket o, as at o², is a movable cutter blade P adapted to coöperate with the fixed blade o' to shear the web when the same is extend- 45 ing between said cutters.

Movable blade P normally gravitates away 50 from the fixed blade o', as shown in Fig. 6, and said movable blade has an arm p at its forward end which extends into the path of a cam track r mounted on the rack carrying member R which is substantially, in its essential particulars, like rack carrying member G, and is operated by a spring similar to spring J.

55 The organization of the parts are such that the web is advanced and projected into the bowl during the elevating movement of the seat, and during the greater part of such elevating movement, the arm p of the movable 60 blade engages a low phase r' of the cam track r. However, as the seat nears the finishing point of its rising movement, the rising phase r² of the cam track r comes into contact with, and elevates, the forwardly projecting arm- 65 p² of the movable blade. This causes the

blade P to be lifted into coöperative relation with the fixed blade o' with the result that the web is cut and the portion extending into the bowl falls loosely therein. When the bowl is subsequently flushed, this portion of 70 the web is carried away.

It will, of course, be understood that the general structure shown in Figs. 4, 5 and 6 is substantially the same as that in Figs. 1, 2 and 3. The modified form of construction is 75 provided with a feed magazine similar to e, the feed roll is advanced by coöperating rack and pinion with a ratchet and pawl connection, and the link s corresponds to the link i' and operates in the same way. A detail de- 80 scription of these parts is, therefore, unessential though the proportions of the parts, in the modified form, may slightly vary from those of the preferred form.

Links i' and s have been hereinbefore de- 85 scribed as attached at their upper ends to a mounting affixed to the bowl. In some bowls it might be difficult to secure a clamp thereon and, accordingly, if desired, the ends of these links, opposite to that which is connected to the rack carrying member, may be attached to the floor in any suitable way. 90 Such a construction is shown in Fig. 7, wherein all of the parts are identical with the showing of Fig. 1, with the exception 95 that the link i'', which corresponds to link i', is secured to the floor on which the bowl rests, instead of directly to the bowl, as shown in Fig. 1.

It thus appears that practically all the 100 mechanism of this invention is mounted upon the seat and the invention may, therefore, be expeditiously installed upon any bowl by simply securing thereto a seat on which the 105 mountings of this invention are secured or by securing the mountings of the invention directly upon the seat in use. In the interest of clearness, the parts are shown larger than need be for their practical operation and in the embodiment of this invention the seat is 110 not in the least encumbered by heavy, unwieldy devices which are of an unsightly character. If desired, the operating mechanism may be entirely incased for sanitary 115 as well as esthetic reasons.

It is frequently desirable to tilt up the seat into a vertical position for the proper 120 cleansing of the bowl and this may be readily accomplished because of the detachable connection between the link i' and the plate i².

The device of the present invention is 125 highly efficient in its operation and is practical in every way. The paper web is advanced with accuracy and, if desired, means may be provided to preclude of a retrograde action thereof. This means may embody a plurality of serrations t along the edge of the discharge casing L, over which the paper runs after passing between the rolls F and F', to be rolled upon shaft l. These serra- 130

tions are so formed that the paper slides freely over the same in its forward travel but is impaled by the sharp points of the serrations when any retrograde movement 5 of the web is made. Thus such movement is precluded so that the web is free to advance only and cannot slip backward over the feed roll.

It will be understood that, while I have 10 illustrated the present invention in its preferred form, the same is capable of slight modifications in adapting the invention to its various environments, such as to seats or bowls of different characters. It is to 15 be understood, therefore, that the invention is not limited to the precise mountings or details of construction hereinbefore described, but is as broadly novel as is commensurate with the appended claims.

20 Having thus fully described the invention, what I claim as new, and desire to secure by Letters Patent, is:

1. In a device of the class described, the combination of a toilet seat mounted for 25 pivotal movement above a bowl and normally elevated slightly above the same, a feed roll positioned at the side of said seat, a protecting web laid across said seat and in contact with the feed roll, a spring, connections between the seat and the spring, which connections place the spring under 30 tension when the seat is depressed, and release the spring when the seat is elevated, driving connections between the spring and 35 the feed roll for operating said roll, when the spring is released, to advance the protecting web across the seat, means for directing the used portions of the web into the interior of the bowl, and means for cutting off the used portions of the web from 40 that portion thereof which remains unused, whereby the flushing of the bowl carries away the used portions of the web.

2. In a device of the class described, the 45 combination of a toilet seat mounted for pivotal movement above a bowl and normally elevated slightly above the same, a feed roll positioned at the side of said seat, a protecting web laid across said seat and 50 in contact with the feed roll, a spring, connections between the seat and the spring, which connections place the spring under tension when the seat is depressed, and release the spring when the seat is elevated, 55 driving connections between the spring and the feed roll for operating said roll, when the spring is released, to advance the protecting web across the seat, means for directing the used portions of the web into the 60 interior of the bowl, and means, operable during the elevating movement of the seat, for cutting off the used portions of the web from that portion thereof which remains unused, whereby the flushing of the bowl 65 carries away the used portions of the web.

3. In a device of the class described, the combination of a toilet seat mounted for pivotal movement above a bowl and normally elevated slightly above the same, a feed roll positioned at the side of the seat, a protecting web laid across said seat and in contact with the feed roll, a stop associated with the feed roll, a loose pinion provided with a pawl co-operating with said stop, a member carrying a rack meshing with the pinion, 70 a spring secured to the rack for normally imparting movement thereto for the purpose of rotating the feed roll, said feed roll, rack and spring being mounted upon, and adapted for movement with, the seat, and 75 a link secured to the rack-carrying member at one end and at its other end to the bowl, whereby the tension of the spring normally maintains the seat in a slightly elevated position and, in elevating the seat from a 80 depressed position, actuates the feed roll.

4. In a device of the class described, a seat pivotally mounted above a bowl and normally elevated slightly above the same, a feed roll at one side of the seat, a spring 90 motor supported on the seat and movable therewith, connections between the spring motor and a fixed support for energizing the spring motor when the seat is depressed, which spring motor elevates the seat when the seat is released, and driving connections between the spring motor and the feed roll for imparting movement to the feed roll during the seat elevating operation.

5. A device for feeding a web of paper 100 across a toilet seat, embodying a seat pivotally mounted above a bowl and normally elevated slightly above the same, a feed roll for the paper web at one side of the seat, a spring, connections between the spring and 105 a fixed support for energizing the spring when the seat is depressed and releasing said spring when seat is elevated, a pinion associated with the feed roll, and a rack co-operating with the pinion, said rack being 110 operatively connected with the spring whereby, when the spring is released, the feed roll is advanced and the web fed across the seat, all of the web advancing mechanism being mounted on the seat and supported 115 thereby.

6. A device for feeding a web of paper across a toilet seat, embodying a seat pivotally mounted above a bowl and normally elevated slightly above the same, a feed roll 120 for the paper web at one side of the seat, a spring, connections between the spring and a fixed support for energizing the spring when the seat is depressed and releasing said spring when the seat is elevated, a pinion 125 loosely associated with the feed roll, a pawl and ratchet connection between the pinion and the feed roll, and a rack co-operating with said pinion and operatively connected with the spring whereby, when the spring is 130

released, the feed roll is advanced and the paper web fed across the seat, but, when the spring is again placed under tension, the pawl rides idly over the ratchet and the feed roll remains stationary, all of the web advancing mechanism mounted on the seat and supported thereby.

7. In a device of the class described, the combination of a toilet seat mounted for pivotal movement above a bowl and normally elevated slightly above the same, a feed roll mounted on said seat at one edge thereof, a protecting web laid across said seat and in contact with the feed roll, a member pivotally supported on the seat, means pivotally securing said member also to a fixed support whereby pivotal movement of the seat oscillates the pivoted member, a spring coöperating with the pivoted member and adapted to be placed under tension by said member when the seat is depressed, said spring normally operating to oscillate the pivoted member into position to elevate the seat, and driving connections between the pivoted member and the feed roll for operating said roll when the seat is elevated to advance protecting web across the seat.

8. In a device of the class described, the combination of a toilet seat mounted for pivotal movement above a bowl and normally elevated slightly above the same, a feed roll mounted on said seat at one edge thereof, a protecting web laid across said seat and in contact with the feed roll, a member pivotally supported on the seat, means pivotally securing said member also to a fixed support whereby pivotal movement of the seat oscillates the pivoted member, a spring coöperating with the pivoted member and adapted to be placed under tension by said member when the seat is depressed, said spring normally operating to oscillate the pivoted member into position to elevate the seat and means for cutting off the used portions of the web from that portion thereof which remains unused.

9. In a device of the class described, the combination of a toilet seat mounted for pivotal movement above a bowl and normally elevated slightly above the same, a feed roll mounted on said seat at one edge thereof, a protecting web laid across said seat and in contact with the feed roll, a member pivotally supported on the seat, a link secured at one end to the pivoted member and precluded against longitudinal movement by a fixed pivot at its other end whereby pivotal movement of the seat oscillates the pivoted member, a spring coöperat-

ing with the pivoted member and adapted to be placed under tension by said member when the seat is depressed, said spring normally operating to oscillate the pivoted member into position to elevate the seat, and driving connections between the pivoted member and the feed roll for operating said roll when the seat is elevated to advance protecting web across the seat.

10. In a device of the class described, the combination of a toilet seat mounted for pivotal movement above a bowl and normally elevated slightly above the same, a feed roll positioned at the side of the seat, a protecting web laid across said seat and in contact with the feed roll, a stop associated with the feed roll, a loose pinion provided with a pawl coöperating with said stop, a member carrying a rack meshing with the pinion, a spring secured to the rack for normally imparting movement thereto for the purpose of rotating the feed roll, said feed roll, rack and spring being mounted upon, and adapted for movement with, the seat, and means for pivotally securing said rack carrying member to a fixed support, whereby the tension of the spring normally maintains the seat in a slightly elevated position and, in elevating the seat from a depressed position, actuates the feed roll.

11. In a device of the class described, the combination of a seat pivotally secured to a bowl, a spring for normally partially elevating the seat, said spring being supported on the seat and bodily movable therewith, a feed roll mounted at one side of the seat, driving connections operable by the spring to actuate the feed roll when the seat is elevated for the purpose of feeding a protecting web across the seat, all of the web advancing mechanism being mounted upon the seat.

12. In a device of the class described, the combination of a feed roll, a spring motor for actuating the feed roll, a hanger for mounting the feed roll and its operating spring motor upon a toilet seat, means coöperating with the spring motor and with a fixed support for normally partially elevating the seat above the bowl with which it is associated, said spring motor being energized when the seat is depressed, and driving connections between the spring motor and the feed roll whereby, when the seat is released, the spring motor elevates said seat and simultaneously operates the feed roll.

In testimony whereof I have signed my name to this specification.

ERNEST SPANOS.
